UNITED STATES PATENT OFFICE.

JOSEPH M. BIANCHI, OF CHICAGO, ILLINOIS.

OIL-BURNER.

1,190,850.

Specification of Letters Patent. Patented July 11, 1916.

Application filed October 9, 1915. Serial No. 54,940.

To all whom it may concern:

Be it known that I, JOSEPH M. BIANCHI, a citizen of the United States, and a resident of the city of Chicago, county of Cook, 5 and State of Illinois, have invented certain new and useful Improvements in Oil-Burners, of which the following is a specification.

My invention relates to improvements in 10 oil burners, and has for its object the provision of an improved construction of this character which is simple and efficient in use.

The invention consists in the combinations and arrangements of parts hereinafter described and claimed.

The invention will be best understood by reference to the accompanying drawing forming a part of this specification, and in 20 which,

Figure 1 is a sectional view of a burner embodying my invention, and Fig. 2, a section taken on line 2—2 of Fig. 1.

The preferred form of construction, as 25 illustrated in the drawing, comprises a hollow globe 3 having a valved supply pipe 4 leading thereto, said pipe passing over said globe and being rebent and threaded in the side thereof, as shown in Fig. 1. A nipple 5 is threaded in the bottom of said globe, said nipple extending upwardly into said globe and downwardly therefrom, the bottom portion 6 of said nipple being made comparatively heavy so as to retain a com- 30 paratively large amount of heat. Escape openings 7 are arranged in the lower portion of nipple 5 below globe 3 and a spider 8 is threaded on said nipple below said globe and just above said escape openings. The 35 spider 8 is provided with radiating arms 9 provided at their outer ends with depending deflector blades 10 having scalloped lower edges 11. A preliminary heating or priming nipple 12 is suspended under cup 5 on a bolt 13 threaded centrally in the bottom of nipple 5 and a lock nut 14 is provided on bolt 13 to lock the parts securely together. The cup 12 is provided with a 40 pad 15 of absorbent non-combustible material adapted to facilitate the use of said cup as a preliminary heating medium for the parts.

In use, the burner is arranged centrally,

as shown under an ordinary stove spider 16 with the side pipe 4 passing over said burner 55 so as to receive the intense heat therefrom. Oil supplied to globe 3 through pipe 4 will rise in said globe until it overflows into the nipple 5 whence it will escape through the openings 7 into the cup 12. The supply of 60 oil being then turned off the oil in cup 12 is lighted and burns to heat up the parts until gas is generated which will be evidenced by the emission of a blue flame through the openings 7. When this occurs, 65 the supply of oil is again turned on through pipe 4 when the burner is ready for use in the usual manner.

The specific arrangement of parts is a simple and effective one for the purpose. 70

While I have illustrated and described the preferred form of construction for carrying my invention into effect, this is capable of variation and modification without departing from the spirit of the invention. 75 I, therefore, do not wish to be limited to the precise details of construction set forth, but desire to avail myself of such variations and modifications as come within the scope of the appended claims. 80

Having described my invention what I claim as new and desire to secure by Letters Patent is:

1. An oil burner comprising a hollow oil receptacle; an oil supply pipe leading thereto; a pipe nipple threaded in the bottom of said receptacle and projecting upwardly thereinto and downwardly therefrom, there being escape openings in said nipple below said receptacle; a spider threaded on said nipple below said receptacle, said spider being provided with deflector blades opposite said escape openings; a supporting member threaded centrally in the bottom of said nipple; and a heating vessel suspended 90 on said member, substantially as described. 95

2. An oil burner comprising a hollow globe; a supply pipe passing over said globe and being rebent and entering the side thereof; a nipple threaded in the bottom of said globe and projecting upwardly thereinto and downwardly therefrom, there being escape openings in said nipple below said globe; a spider threaded on said nipple below said globe, said spider being provided 100 with a plurality of radiating arms having 105

depending deflector blades at their outer ends opposite said escape openings; a supporting bolt threaded centrally in the bottom of said nipple; a lock nut on said bolt 5 contacting with the bottom of said nipple; and a preliminary heating vessel suspended on said bolt, substantially as described.

In testimony whereof I have signed my name to this specification in the presence of two subscribing witnesses.

JOSEPH M. BIANCHI.
